(57) **CLAIM**

The ornamental design for a mobile phone, as shown.

DESCRIPTION

FIG. 1 is a front elevational view of a first embodiment of a mobile phone showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is a front elevational view of a second embodiment of a mobile phone showing my new design;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof;

FIG. 14 is a perspective view thereof;

FIG. 15 is a front elevational view of a third embodiment of a mobile phone showing my new design;

FIG. 16 is a rear elevational view thereof;

FIG. 17 is a left side elevational view thereof;

FIG. 18 is a right side elevational view thereof;

FIG. 19 is a top plan view thereof;

FIG. 20 is a bottom plan view thereof;

FIG. 21 is a perspective view thereof;

FIG. 22 is a front elevational view of a fourth embodiment of a mobile phone showing my new design;

FIG. 23 is a rear elevational view thereof;

FIG. 24 is a left side elevational view thereof;

FIG. 25 is a right side elevational view thereof;

FIG. 26 is a top plan view thereof;

FIG. 27 is a bottom plan view thereof;

FIG. 28 is a perspective view thereof;

FIG. 29 is a front elevational view of a fifth embodiment of a mobile phone showing my new design;

(Continued)

FIG. 30 is a rear elevational view thereof;
 FIG. 31 is a left side elevational view thereof;
 FIG. 32 is a right side elevational view thereof;
 FIG. 33 is a top plan view thereof;
 FIG. 34 is a bottom plan view thereof;
 FIG. 35 is a perspective view thereof;
 FIG. 36 is a front elevational view of a sixth embodiment of a mobile phone showing my new design;
 FIG. 37 is a rear elevational view thereof;
 FIG. 38 is a left side elevational view thereof;
 FIG. 39 is a right side elevational view thereof;
 FIG. 40 is a top plan view thereof;
 FIG. 41 is a bottom plan view thereof; and,
 FIG. 42 is a perspective view thereof.
